ENGINE TIMING DEVICE

Albert B. Rauscher, Parnassus, Pa.

Application January 8, 1945, Serial No. 571,891

1 Claim. (Cl. 33-207)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to devices for checking the timing of aircraft and other internal combustion engines. Among other objects, it aims to provide a simple and practicable timing device which is used without removing the propeller of the aircraft, and thus saves a great deal of time and labor, since certain parts of a propeller must be carefully cleaned before re-assembling. Other objects will be apparent from the following description of a preferred embodiment of the invention shown in the accompanying drawings, wherein:

Fig. 1 is an elevation of the device showing the timing plate and the pointer or needle, the latter being shown swung out of its normal vertical position;

Fig. 2 is a sectional view of the device showing in dash lines a propeller hub on which the device is mounted.

Referring particularly to the drawings, the preferred form of timing device consists of a back plate or support 5 having means for securing it to a propeller hub, a timing plate 6 secured in front of the back plate and provided with one or more scales, and a pointer 7 swingably mounted in front of the timing plate and adapted to give readings on said scales as will be described. The back plate may be a circular metal or other rigid plate and may have three or more channel members 8 fixed to the back face and each extending radially from the center and providing T-slots in which the right angularly bent ends 9a of arms 9 may slide. Arms 9 are adapted to embrace the propeller hub 10, and a flexible strap 11 may be secured to one or more of the arms and may be wrapped around the remaining arms and the hub and secured, as by a buckle 12, so that the back plate will be non-rotatably held on the hub. Wing nuts 13 threaded on studs 14 projecting from the bent arm ends 9a may be tightened against the channel members 8 to clamp the arms in adjusted positions radially of the back plate. Thus the back plate is held rigidly at right angles to the axis of the hub and substantially centered relative to the same, thereby providing a desirable support for the pointer and timing plate by which readings are taken.

At the center of the back plate a hole 15 is drilled to receive a bolt 16 having a smooth shank portion 17, a threaded portion 18 and a reduced

threaded end portion 19. The smooth portion 17 fits snugly in hole 15, while the threaded portion 18 fits in a central bore 20 in the timing plate 6. A nut 22 threaded on bolt portion 18 makes it possible to tighten the timing plate on the back plate. The necessary washers, not designated by reference numerals, may also be used. The pointer or needle 7 is rotatably supported on the bolt 16, preferably having a ball bearing 23 fitted into a bore provided half way between its ends, said ball bearing being carried by the reduced screw threaded portion 19. A nut 24 and lock nut 25 secure the needle or pointer to the bolt, while permitting free swinging because of the ball bearing. A weight 26 may be secured by a stud 27 and nut 28 to one end of the pointer, the other end being preferably pointed, and always being uppermost, because of the weighted end, except when swung by the operator. Both ends of the pointer preferably project beyond the edges of the scale or timing plate, and a straight scribed line 29 extends centrally of the pointer from end to end. The pointer is transparent, being preferably made from a plastic such as polystyrene or methyl methacrylate, and the scribed line 29 may be lined up visually with graduations 30 on various scales marked or supported on the timing plate, thereby to give readings. The timing plate may be made of metal or a plastic, and preferably is opaque. It is shown as having six scales thereon, for six different gear reduction ratios of the propeller-engine assembly. These ratios may be 1:1, 2:1, 3:2, 4:3, 16:11 and 16:9 as shown. Scales for other ratios may of course be provided. The upper half of the timing plate has three of these scales and the lower half has the other three. While the pointer always is upright, the timing plate may be inverted from the position shown in Fig. 1 by merely loosening nut 22 and turning the timing plate on the axis of bolt 16, whereupon the three lower scales will be uppermost, which will facilitate reading them. Thus the zeros of all six scales may be visually aligned with the scribed line 29 on the upright pointer, which properly fixes the position of each scale prior to using the device for checking timing of the engine.

Assuming that the device is installed on a propeller hub and that the propeller axis is horizontal, or nearly so, with the pointer vertical, or nearly so, the operator will turn the propeller manually until any selected one of the engine pistons is at top dead center. Then the timing plate is rotated to bring the zero of the proper

scale exactly in line with the scribed line on the pointer. Then to check the timing, the propeller is rotated manually until the ignition point for the cylinder of the piston initially selected is reached. This rotation of the propeller will necessarily swing the hub through a certain angle, and the timing plate must also turn through the same angle. But the pointer remains upright, and hence the amount of movement of the selected piston in its cylinder may be read by referring to the proper scale. The operator, knowing what this movement should be, or consulting tables in the event he is uninformed, will immediately detect any deviation from the proper figure and can adjust the engine 15 to correct the timing of the particular cylinder being tested.

It will be obvious that the device will save a vast amount of time and labor when checking the timing of aircraft engines. Probably the device will be useful if adapted for other types of internal combustion engines.

What I claim is:

A timing device for multicylinder internal combustion engines in aircraft, said device comprising a supporting means including a vertical supporting plate having detachable members thereon to embrace and clamp the hub of an aircraft propeller, said members being adjustable on said plate and having fastening means thereon for holding them securely upon the hub in longitudinal alignment therewith whereby the device will be suitable for use on hubs of various sizes, a scale plate having selectively concentric scale indicia indicative of gear reduction ratio between the propeller and the engine marked thereon for checking the timing of the cylinders, each scale extending only through a half circle, means to support the scale plate upon the sup-

porting plate so that it is angularly adjustable relative to the latter that normally turns with the supporting plate and the hub, and a transparent pointer of greater length than a normal propeller hub diameter, said pointer being swingably mounted on said scale support, the swing axis of said pointer and plate cutting a prolongation of a longitudinal axis of the hub, a flat weight at the lower end of said pointer and said pointer being hence adapted to lie in a plumb line irrespective of movements of the scale plate and having a single indicating line on its longer axis whereby to overlie points on all of the scale indicia and so to enable the timing of the aircraft engine to be checked without removal of the propeller.
